UNITED STATES PATENT OFFICE.

ANTON T. LUECKENBACH, OF NEENAH, WISCONSIN.

PRESS-ROLL FOR PAPER-MAKING MACHINES.

1,209,736.

Specification of Letters Patent. Patented Dec. 26, 1916.

Application filed May 29, 1916. Serial No. 100,630.

To all whom it may concern:

Be it known that I, ANTON T. LUECKENBACH, a citizen of the United States, residing at Neenah, in the county of Winnebago and State of Wisconsin, have invented a new and useful Press-Roll for Paper-Making Machines, of which the following is a specification.

My invention relates to the making of a roll the outer surface of which is of wood, and the object of the improvement is to form a wood surfaced roll that will have a uniform density and a smooth even surface, one that is not formed of a solid log, as logs that are of a diameter, length and quality suitable for such rolls are not only very scarce and difficult to obtain, but often require transportation many hundred miles and at a great cost, while by my improved method of making the rolls from plank, the rolls can be made at a comparatively small cost.

My invention consists of building a wood surface upon a metallic core and forming a series of ribs longitudinally arranged around the core of such form as will be adapted to hold a stave between said ribs, and then fitting staves in between the ribs entirely around the core, and it is shown in the accompanying drawing in which,—

Figure 1 is a side elevation of a roll and its journals, the central circumferential surface of the roll being broken and showing the roll core. Fig. 2 is a longitudinal section of the roll, on line 3, 3, of Fig. 3. Fig. 3 is an end elevation of the roll. Fig. 4 is a plan of one of the staves which forms the outer surface of the roll, broken in its length. Fig. 5 is a perspective view of one end of a stave. Fig. 6 is an end view of a stave of a modified form from the one shown in Fig. 5. Fig. 7 is a fragment of the core in section upon the line 2, 2, of Fig. 2.

Similar numerals indicate like parts in the several views.

1, indicates the journals of the roll; 2, the body of the roll core which may be of any length and diameter that is required in any one case. This body is provided with a series of ribs 3, which are arranged in parallel relation around the core lengthwise of the roll, the ribs being provided each with a T shaped head somewhat like the tread of a railroad rail, it being essential that the

ribs 4, each have an overhanging flange 5, upon opposite sides of the rib that is adapted to retain a wood stave in contact with the outer surface 6 of the core body when fitted to and driven in between two ribs. The overhanging part 5 of each rib is curved where it joins the web 11, and around its entire outer surface and the stave for covering the roll has its grooves 9, for fitting the ribs correspondingly curved, so that there are no angular corners in the grooves in the staves from which a split in the wood will be liable to start. Staves 7, are to be made of plank of a kind of wood and quality suitable for the outer surface of the roll and of a width and thickness required for any particular roll. Upon the edges 13, grooves 9 are to be formed for receiving the overhanging flange 5, of the rib, and inside of said grooves the edges 10 are to be made parallel and the edges 13 radially formed and the stave made of such width as will permit it to be driven in between the webs 11 of two ribs, and in close contact with the surface 6 of the core. The part 12 of the stave that is above or outside of the rib is formed into a wedge shape as is shown in Fig. 4, with the edges 13 thereof formed radially and so that the end of a finished roll will present a wide end 14, and narrow end 15, alternately of the staves.

In making the roll, the staves are all made from one pattern with their inner surface provided with parallel edges and their outer surface with tapering edges, and the grooves 9, made parallel with the inner edges. The staves should be a little longer than the finished roll is to be and after all the staves have been driven in, the roll is to be suspended in a lathe upon the core centers and the ends of the staves cut off to the required length and the surface of the roll turned off until a round and smooth surface is produced. After use, should one or more of the staves show a defect which destroys its usefulness, said stave or staves can be driven out and those that are perfect driven in, cut to the required length and the roll turned off until a smooth surface is obtained.

I am aware that rolls have been made with a wood surface upon a metallic core, such for instance as the rolls patented by William C. Nash, February 9, 1909, Nos. 912,254 and 912,255, in which the wood sur-

face is formed of a plurality of blocks of wood with the grain of the wood radially arranged, end rings and bolts through the rings and cores being used to clamp the blocks together upon the rolls.

Having described my invention, what I claim and desire to secure by Letters Patent, is,—

1. A wood surfaced paper machine roll comprising a metallic core adapted for revolution in journal bearings and having a comparatively smooth outer surface, a plurality of ribs longitudinally arranged and parallel, along the outer surface, a T head upon each rib adapted to retain a stave between the T heads of two adjoining ribs, and staves fitted upon their inner surfaces to contact with the outer surface of said core between the webs of adjoining ribs and under the flanges of the T heads of said ribs and their outer portion provided with radially formed edges which taper from one end to the other and are adapted to be driven in between adjoining ribs around the roll with the wide ends of the staves alternately arranged.

2. In a wood surfaced roll for a paper making machine having a metallic core and a plurality of ribs having T shaped heads upon their outer ends, a stave for covering said core of a length equal to the length of the finished roll having a groove upon its opposite edges adapted to be engaged by the T head of a rib, the part of the stave inside of said groove having parallel edges adapted to fit in between the webs of adjoining ribs and the inner surface of the stave to lie in close contact with the outer surface of the core, and the part that is outside of said ribs having its edges made

radial and tapering from one end of the stave to the other.

3. A stave for the outer surface of a paper making machine roll which is adapted to be retained upon the outer surface of a metallic roll core between parallel ribs having T shaped heads for retaining the staves upon the core, consisting of a plank formed of wood of a length equal to the length of the finished roll, its inner face being adapted to lie in contact with the outer surface of said core between two of said ribs, a groove along opposite edges of the stave in parallel relation, the edges of the stave inside of the grooves being fitted for being driven in between the webs of adjoining ribs, and the part of the staves that is outside of the ribs having its edges projecting an equal distance outside of the edges of the part that is inside of the grooves formed radially and made tapering from one end of the stave to the other.

4. A wood surfaced paper machine roll comprising a metallic core adapted for revolution in journal bearings and having a comparatively smooth outer surface, a plurality of ribs each having a thin connecting web extending at equal spaced distances apart, radially from around said outer surface arranged longitudinally and parallel, a T head upon the outer extremity of each web, the connections of said heads with the webs and around said T heads being curved surfaces for their less tendency to start a split in the wood covering than if there were sharp angles upon the T heads.
